(57) **CLAIM**

The ornamental design for an atomizer for inhaler, as shown and described.

DESCRIPTION

FIG. 1 is a front, top, and left side perspective view of an atomizer for inhaler showing our new design;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof; and,

FIG. 8 is a cross-sectional view taken in the direction of line 8-8 shown in FIG. 4.

The atomizer for inhaler is fabricated from translucent materials. The broken line showing of interior portions of the article is included for the purpose of illustrating structural environment and forms no part of the claimed design.
